UNITED STATES PATENT OFFICE.

LESTER R. WELLMAN, OF CHICAGO, ILLINOIS, ASSIGNOR TO FRIEDLY-VOSHARDT CO.,
OF CHICAGO, ILLINOIS, A CORPORATION OF ILLINOIS.

DESIGN FOR A TWO-LIGHT SHOWER-PLATE.

57,802.

Specification for Design.

Patented May 3, 1921.

Application filed June 28, 1920. Serial No. 392,528. Term of patent 7 years.

To all whom it may concern:

Be it known that I, LESTER R. WELLMAN, a citizen of the United States, residing at Chicago, in the county of Cook and State of Illinois, have invented a new, original, and ornamental Design for a Two-Light Shower-Plate, of which the following is a specification, reference being had to the accompanying drawing, forming a part thereof.

Fig. 2 is a plan view of the same.

I claim:

The ornamental design for a two-light shower plate, as shown.

LESTER R. WELLMAN.
